United States Patent Office

Des. 232,199

Patented July 23, 1974

232,199

ELECTRIC SHAVER

Hermann R. Schaefer, Bridgeport, Conn., assignor to
Sperry Rand Corporation, New York, N.Y.

Original design application Nov. 16, 1970, Ser. No.
25,997. Divided and this application Aug. 30, 1972,
Ser. No. 280,744

Term of patent 14 years

Int. Cl. D28—03

U.S. Cl. D95—3 A

Fig. 7.

FIG. 1 is a rear top and right side perspective view of a shaver showing my new design;

FIG. 2 is a right side elevational view;

FIG. 3 is a rear elevational view;

FIG. 4 is a left side elevational view;

FIG. 5 is a top view;

FIG. 6 is a bottom view; and

FIG. 7 is a front elevational view thereof.

This application is a division of copending application Ser. No. 25,997, filed Nov. 16, 1970, and now Pat. No. D. 226,050 as of Jan. 16, 1973.

I claim:

The ornamental design for an electric shaver, substantially as shown and described.
